DESIGN FOR A TEMPERATURE AND HUMIDITY INDICATOR HOUSING

Garfield L. Beckstrom, Chicago, Ill., assignor to
Autopoint Company, Chicago, Ill., a corpora-
tion of Illinois

Application January 26, 1948, Serial No. 144,042

Term of patent 14 years

(Cl. D52—7)

To all whom it may concern:

Be it known that I, Garfield L. Beckstrom, a citizen of the United States, residing at Chicago, in the county of Cook and State of Illinois, have invented a new, original, and ornamental Design for a Temperature and Humidity Indicator Housing, of which the following is a specification, reference being had to the accompanying drawing, forming a part thereof.

In the drawing:

Figure 1 is a top plan view of a temperature and humidity indicator housing, embodying my new design;

Fig. 2 is a bottom plan view of the same;

Fig. 3 is a view in front elevation of the same;

Fig. 4 is a view in side elevation of the same; and

Fig. 5 is a view in rear elevation thereof.

I claim:

The ornamental design for a temperature and humidity indicator housing, substantially as shown.

GARFIELD L. BECKSTROM.
